No. 694,453.

Patented Mar. 4, 1902.

B. E. ANDRESS.

DEVICE FOR DELIVERING TRAIN ORDERS.

(Application filed Jan. 30, 1901.)

(No Model.)

UNITED STATES PATENT OFFICE.

BERT E. ANDRESS, OF PORT ALLEGANY, PENNSYLVANIA.

DEVICE FOR DELIVERING TRAIN-ORDERS.

SPECIFICATION forming part of Letters Patent No. 694,453, dated March 4, 1902.

Application filed January 30, 1901. Serial No. 45,341. (No model.)

To all whom it may concern:

Be it known that I, BERT E. ANDRESS, of Port Allegany, in the county of McKean, in the State of Pennsylvania, have invented new and useful Improvements in Devices for Delivering Train-Orders, of which the following, taken in connection with the accompanying drawings, is a full, clear, and exact description.

My invention relates to a device for delivering train orders and messages to engineers and conductors of moving cars or trains, the object being to provide a simple and practical means whereby the operator or attendant at any station along the line of a railroad may be able to deliver train orders and messages to the engineer, conductor, or other member of the crew of a train without reducing the speed of the train and without endangering the lives of the persons delivering and receiving the orders or messages.

To this end the invention consists in the construction, combination, and arrangement of a device for the purpose mentioned, as hereinafter fully described, and pointed out in the claims.

Referring to the drawings, Figure 1 is a perspective view of my invention, showing the method of operating the same. Fig. 2 is an enlarged perspective view of the parts seen in Fig. 1 of the detached pole and the support for the train order or message, the lower end of the pole being broken away. Fig. 3 is an inverted plan view of the adjacent ends of the pole and message-supporting frame shown in their assembled positions. Fig. 4 is an end view of the pole, showing particularly the spring clamping-jaws. Fig. 5 is a sectional view taken on line 5-5, Fig. 2.

Similar reference characters indicate corresponding parts in all the views.

It is well known that when the operator or other attendant at a railway-station is desirous of delivering a train order or message to any member of the crew he is obliged to approach very closely to the train and the engineer is obliged to lean or reach far out of the cab in order to insure the safe delivery and reception of the order or message. These orders or messages are usually delivered to the engineers or conductors while the train is in motion and very often running at a high

rate of speed, and owing to the fact that there is always more or less permanent structures in the vicinity of the station and in close proximity to the track and also that frequently cars are left on sidings near the station the person receiving the order or message on the train frequently comes in contact with one of these structures or side-track cars and is seriously injured. On the other hand, when the train is moving at a high rate of speed the suction of air incidental to the motion of the train and also the projecting steps of the cars endanger the lives of the operator or station attendant, particularly in winter.

My invention is designed to reduce to a minimum these dangers, and preferably consists of a rod or pole A and a clamp B, detachably supported at one end of the rod or pole A and adapted to receive and retain a train-order or other message.

The rod or pole A may be of any desired form or material, is preferably formed of wood or other light material, and is provided at one end with a pair of spring-jaws a and a square or angular portion a', the opposite end of said rod or pole being adapted to be engaged by the station attendant or operator for holding the rod or pole in the desired position. The clamp B may also be of any desired form or construction for receiving and retaining the train order or message which it may be desired to deliver to the engineer or other member of the train-crew and preferably consists of a bar b, formed of wire or other suitable material, and a yielding tongue or arm b', having one end secured to the bar in proximity to one of its ends and its other end movable toward and away from the adjacent face of said bar b in proximity to its other end, the free end of the arm or tongue b' being normally tensioned toward the bar b. The clamp B is usually mounted upon a suitable loop or ring C, also formed of wire and provided with an arm c and a pair of spring-jaws c'. The loop C, arm c, and jaws c' are usually formed from a single piece of wire, one end being suitably bent for forming the jaws c' and the other end being bent in the form of a ring and having its extremity hooked or otherwise secured to one end of the arm c, the jaws c' forming the opposite extremity of said arm c. The portions of the wire ring or loop adjacent to the arm

are usually bent outwardly at diverging angles for forming suitable depressions 1 and shoulders 2, which are adapted to receive the opposite ends of the clamping-bar *b* for holding the same in its operative position. The shoulders or arms 2 preferably terminate in inwardly-converging arms 3, one of which forms the continuation of the arms *c*, the extremity of the other arm 3 being hooked upon or secured to the adjacent ends of the arms *c* and 3.

The bar *b* is preferably formed of a single piece of wire having its intermediate portion looped upon one of the arms or shoulders 2 in one of the depressions 1, and its opposite ends are suitably bent upon or otherwise secured to the opposite arm or shoulder 2 in the adjacent depression 1.

As previously stated, the clamp *B* and loop *C* are adapted to be supported upon the rod or pole *A* in such manner as to be readily detached therefrom by the engineer or other member of the crew who may be assigned to receive the train order or other message from the operator. In order to permit said clamp *B*, containing the train order or message, to be thus readily removed, a portion of the arm *c* is inserted between the spring-jaws *a* and the jaws *c'* are engaged with the opposite faces of the square portion *a'* of the rod or pole *A*. In forming the jaws *c'* I usually bend the wire in such manner as to form a suitable stop bar or bars 4, which engages one of the faces of the square portions *a'* and serves to additionally hold the clamp *B* and loop *C* upon the rod or pole, it being understood that the clamping-jaws *a'* serve to hold the clamp *B* and loop *C* in operative position and at the same time permits the clamp to be readily detached from said jaws by the engineer or other member of the crew when desired.

In the operation of my invention the train order or message is slipped or passed between the spring-arm *b'* and the bar *b*, the arm *b'* serving to hold the order or message in position. The jaws *c'* are then registered with the opposite faces of the portion *a'* of the pole *A* and the arm *c* is forced between the spring-jaws *a*. The operator is then enabled to stand at a considerable distance from the train moving at a high rate of speed and to hold the loop in close proximity to the moving train and in such position that the engineer or conductor or any member of the crew may readily insert his arm through the loop or even catch the ring by hand, whereupon the arm *c* and the clamp *B* are readily detached from the pole. The message is then removed by the member of the crew receiving the same and the clamp thrown back to the operator or in close proximity to the station where any of the station attendants may readily recover the same to be reused when desired. When the clamp and pole are assembled, the open ends of the loops *a* and *c'* are opposite to each other, and when the train is approaching the operator the bent

end of the loop *a* is usually turned in the direction of the movement of the train in order that the ring and clamp may be more readily detached by the person receiving the order or message.

The operation of my invention will now be readily understood upon reference to the foregoing description and the accompanying drawing, and it will be noted that considerable change may be made in the detail construction and arrangement of the parts of my invention without departing from the spirit thereof. Therefore I do not limit myself to the precise construction and arrangement shown and described.

Having thus fully described my invention, what I claim, and desire to secure by Letters Patent, is—

1. A delivery device for train orders or other messages comprising a rod or pole and a message-clamp consisting of a bar and a yielding tongue detachably secured to the pole and provided with a hand-engaging loop united to the opposite ends of the bar.

2. A delivery device for train orders or other messages comprising a rod or pole provided with spring-jaws, and a message-clamp detachably held by said jaws and consisting of a loop having a cross-bar, and a tongue on the bar for the purpose described.

3. A delivery device for train orders or messages comprising a rod or pole and message-receiving support having a loop or ring for the purpose described, a bar having its opposite end secured to the opposite sides of the ring or loop, and a tongue having one end secured to the bar and its other end spring-tensioned toward the bar.

4. A delivery device for train orders or messages comprising a rod or pole having one end provided with spring-jaws and inserted between the jaws and a message-receiving support having one end provided with spring-jaws for engaging the pole and its other end provided with a loop having a spring-arm for holding a message.

5. A delivery device for train orders or other messages comprising a rod or pole having one end provided with yielding clamping-jaws, and a ring detachably held by said jaws and having a cross-bar and spring-arm tensioned toward the bar for engaging and holding the message in position.

6. A delivery device for train orders or messages comprising a rod or pole, spring-jaws secured to the pole, a ring or loop having an arm detachably engaged with the jaws of the pole or rod and provided with a cross-bar and a spring-arm secured at one end to the bar and having its other end tensioned toward the bar for holding the message in position.

In witness whereof I have hereunto set my hand this 8th day of January, 1901.

BERT E. ANDRESS.
